UNITED STATES PATENT OFFICE.

WALTER CHOCLIE SULLENDER, OF ST. LOUIS, MISSOURI.

CAMERA-SHUTTER.

1,153,141.

Specification of Letters Patent. Patented Sept. 7, 1915.

Application filed January 8, 1915. Serial No. 1,143.

To all whom it may concern:

Be it known that I, WALTER C. SULLENDER, a citizen of the United States, and a resident of St. Louis and State of Missouri, have invented certain new and useful Improvements in Camera-Shutters, of which the following is a specification.

My invention relates to photographic cameras, and one of the main objects thereof is to provide means for delaying or determining the moment of exposure without interference with the duration of the exposure, whereby the operator will have time to be included in the photographic picture.

15 A further object is to provide means for making an instantaneous exposure at such predetermined delayed moment.

20 A further object is to provide means for making a time exposure of any desired length at such delayed moment.

25 A further object is to provide such a device which may be attached to conventional cameras, as of the hand type, without any material alteration thereof if any; and further objects are to provide such devices which are simple in construction and use; positive in action; well adapted to the purpose for which they are intended; and comparatively inexpensive.

30 My invention is fully described in the following specification, of which the accompanying drawings form a part, in which like reference characters are used to designate like parts in each of the views, and in

35 which:—
Figure 1 is a vertical section taken through my invention on the line 1—1 of Fig. 2; Fig. 2 is a side elevation of the device, looking from the left of Fig. 1; Fig. 3 is a fragmentary view of certain of the operative parts in different positions than as shown in Fig. 1; Fig. 4 is a similar view with the parts in still different positions; Fig. 5 is an enlarged, fragmentary, section 40 taken on the line 5—5 of Fig. 1; and Fig. 6 is a detached, rear, view on a reduced scale of the shutter disks shown in said preceding figures.

45 In the drawings forming a part of this application I have shown a present preferred form of embodiment of my invention, and in which 7 and 8 represent supporting plates for the mechanism to be described connected by means of posts 9, as 50 in an ordinary clock.

At 10 I have shown a shaft adapted to be rotated by means of a key 11 to wind a clock spring 12 secured to said shaft and to one of the posts 9, said shaft carrying a ratchet 13 normally engaged by a pawl 14 carried by a gear 15 connected with a fan governor 16 through a train of gears 17, as in an ordinary clock, a thumb lever 18 being provided which may be moved into or out of the path of movement of said governor to prevent or 55 permit such movement. The shaft 10 also has a pinion 19 secured thereto which is enmeshed with a gear 20 carrying a pin 21 adapted to impinge on an off-set 22 on a vertically guided rod 23 normally held in uppermost position by means of a coil spring and the lower end of which is pivoted to a latch 24 pivoted to the plate 8 at 25, Fig. 1, and said rod carries a button 26 at its upper end, above the plates 7 and 8, and on 70 the outer side of the camera to give access thereto.

At 27 I have shown a shaft journaled in the plates 7 and 8 and tensionally held against rotation by means of cup springs 28, 80 Fig. 5, said shaft carrying an integral disk 29 having an aperture 30 normally in line with the lens 31, Fig. 2, of the camera; said disk carries a finger 32 at one side of the center, and a projecting portion 33 forming 85 a shoulder, and the top of said disk, in its normal position, is cut away on a substantially horizontal line to form a cam edge.

Closely adjacent the disk 29 and freely revoluble on the shaft 27 is a disk 34 having 90 four pins 35, 36, 37, and 38 arranged thereon adjacent its edge and passing over the plane of the disk 29 and closely adjacent the periphery thereof, and the disk 34 is also provided with an aperture 34^a normally arranged at an angle of 45 degrees with respect to the shaft 27 and aperture 30, but adapted to register with the aperture 30 when the disk 34 is revolved as later explained, and the upper edge of this disk is 95 also cut away to form a cam surface 39 in normal register with that on the disk 29.

Resting upon the upper edges of the disks 29 and 34 is an angular rod 40 secured to a shaft 41 having two arms 42 and 43 thereon, 100 the former of which is adapted to be carried into the path of the governor 16 when the shaft 41 is rocked in the raising of the rod 40 by the revolution of the disks 29 and 34, one or both, and the latter of which is con- 110

nected with a coil spring 44 normally holding the arm 42 out of the path of said governor.

Pivoted at 45 to the disk 34 is a slide 46 of spring material, guided by posts 47 and 48, and having a projection 49 thereunder against which bears a leaf spring 50 the action of which is to force the slide 46 toward the left of Fig. 1 and thus revolve the disk 34, the post 47 limiting this movement, and the outer end of said slide is bent downwardly in order that it may be engaged by a finger of the operator to withdraw said slide against its spring; said slide also carries a tooth 51 on its upper surface adapted to be engaged by the latch 24 to hold said slide in retracted position when manually moved thereinto.

Pivoted at 52 is a hooked lever 53 having a pull button 54 connected with the upper end thereof and by means of which said lever may be moved into the dotted position shown, and in which position it is in the path of the pin 35 on the disk 34, and said lever may be frictionally held in either of its two positions. The hooked end of this lever, when in the dotted position, is also in the path of movement of a supplemental fan governor 55 connected, by means of a train of gears 56, with a shaft 57 having a winding key 58 thereon to wind up a clock spring 59, said shaft also carrying the gear 60 of said train of gears freely revoluble thereon, a ratchet 61 secured thereto and engaged by a pawl 62 carried by the gear 60, and an indicator 63 movable over a dial 64, this ratchet 61 having sixty teeth corresponding to the number of seconds in a minute; the ratchet 61 has an arm 65 secured thereto which projects beyond the periphery thereof to normally bear against the lower end of a lever 66 pivoted at 67, the upper end of which is engaged with a slide-bar 68 guided by posts 69 and 70 thereover, and 71 thereunder; said bar has two upwardly directed projections 72 and 73 which are adapted to impinge upon the posts 69 and 70, respectively, to limit the movement of said bar, in one direction by means of the arm 65 on the ratchet 61 and in the opposite direction by means of a spring 74, and it will be noted that said bar 68 may be moved into the path of movement of the pin 37 on the disk 34.

For instantaneous hand camera exposures, the thumb lever 18 is moved into the position shown in full lines in Fig. 1 and the slide 46 is drawn out from the position of the parts shown in Fig. 4 to those shown in Fig. 1; this slide movement first moves the shutter 34 through an arc of 45 degrees at which time the pin 38 engages the finger 32 and both disks are moved through another arc of 45 degrees; the aperture 30 is now in register with the lens 31 but the aperture

34^a is below the aperture 30, having moved through an arc of 90 degrees whereas the aperture 30 has moved but 45 degrees. This slide movement has carried the tooth 51 thereon beneath and past the latch 24 which descends and locks the shutter in "set" position. When the button 26 above the device is pressed downwardly the latch 24 releases the slide 46 and the spring 50 forces it to the left through an arc of 45 degrees of a circle and brings the aperture 34^a into register with the aperture 30 and lens 31 and the exposure is made; at this instant the pin 38 strikes the shoulder 33 and both disks are revolved through an arc of 45 degrees, 75 into the positions shown in Fig. 4. When it is desired to make a time exposure under ordinary conditions the slide 46 is again "set" as described, the button 54 being then drawn outwardly to move the hooked lever 53 in the path of the pin 35; when the button 26 is depressed the shutter 34 revolves through an arc of 45 degrees to carry the aperture 34^a into register with the aperture 30 and lens 31, but, at this instant, the pin 35 strikes against the hooked lever 53 and the further revolution of the disk 34 is prevented; when a sufficiently long exposure has been made, the button 54 is forced inwardly to release the pin 35 from the lever 53 and both disks are carried into the positions shown in Fig. 4, the exposure having been made. In this connection it will be noted that, in the setting of the shutter, the disk apertures do not jointly register with the lens, and the plate or film is not, therefore, fogged.

When it is desired to delay an instantaneous exposure, as in the event of the operator desiring to be included in the photograph, the thumb lever 18 is moved into the full line position, and the key 11 turned to rotate the shaft 10 and thus revolve the gear 20 until the pin 21 thereon disengages the off-set 22 and allowing the rod 23 to rise. The shutter having previously been "set" as described, the operator may now move the thumb lever 18 into dotted line position and move into the field of the camera; the gear 20 may only move at a speed determined by the wind resistance of the governor 16, and a considerable period passes before the pin 21 is carried around to the top of the off-set 22 to depress the rod 23 and release the slide 46 to make the exposure; while it is preferable to give as much time as possible before the exposure, the operator need not turn the gear 20 entirely around, but may be guided by experience in allowing himself only the necessary time between "setting" and exposure. For a delayed time exposure the last operation of "setting" the camera is repeated, the key 58 being then turned to revolve the ratchet 61 for a distance of as many teeth thereon as the number of sec- 100 105 110 115 120 125 130

onds of the desired exposure, this ratchet movement being without any effect on the gear 60 of the train of gears 56; in this ratchet movement the arm 65 thereon had 5 receded from the lever 66 which may then be moved by the spring 74 to carry the slide 68 into the path of the pin 37, the pin 36 at this time preventing revolution of the governor 55. The key 11 may now be turned 10 to "set" the shutter as already described for the delayed instantaneous exposure, and the operator may move into the field of the camera.

When the rod 23 is depressed by the pin 15 21 on the gear 20 the disk 34 revolves through an arc of 45 degrees to register the aperture 34^a with the lens, but at this instant the pin 37 on the disk 34 strikes against the slide 68 and the further movement of 20 the said disk is prevented, the parts now being in the positions shown in Fig. 3; this movement of the disk has moved the arm 42 into the path of the governor 16 and has released the governor 55 which begins to 25 revolve and continues to do so until the arm 65 on the ratchet 61 moves the slide 68 into normal position, at which time the disk 34 is released and the shutter closes, the pin 35 automatically moving down to lock the governor 55 against revolution.

The governor 55 is so constructed as to insure a speed of movement to the ratchet 61 equal to one second of time for the distance between two teeth and, if the ratchet 35 has been moved five teeth in "setting", the duration of the exposure will be five seconds. Inasmuch as it is not desirable to permit more unwinding of the clock spring 12 than is necessary to release the shutter, 40 I employ the arm 42 to block the governor 16, this being done by the rod 40 being raised from the short radius of the disk 34 at the cam to the longer radius thereof, and I may employ the indicator 63 and dial 64 45 on the outside of a camera to enable the operator to "set" the device for any desired duration of exposure.

It will thus be seen that I may use a camera provided with my invention in the usual way, and I may also materially delay either instantaneous or time exposures and make the latter of any number of seconds duration up to one minute, there being sixty teeth on the ratchet 61.

55 While I have shown a present preferred form of embodiment of my invention, I do not limit myself thereto, but may make changes thereover, within the scope of the following claims, without departing from the spirit of my invention or sacrificing its advantages.

Having fully described the invention, what I claim as new, and desire to secure by Letters Patent, is:—

65 1. The combination with the lens of a

camera; of a movable element provided with an aperture in normal register with said lens, a supplemental element provided with an aperture normally out of register therewith, means for moving said last named element to carry its aperture into register with said lens, means for moving both said elements to carry both apertures out of register with said lens, means for setting said elements, means for releasing the same, 70 means for delaying the movement of said elements after being released, and means for controlling the duration of time between the movement of said first moved element, and of both elements. 75

2. The combination with a lens of a camera; of a movable element provided with an aperture in normal register with said lens, a supplemental element provided with an aperture normally out of register therewith, means for moving said last named element to carry its aperture into register with said lens, means for moving both said elements to carry both apertures out of register with said lens, means for setting said elements, means for releasing the same, 80 means for delaying the movement of said elements after being released, and a train of gears, spring actuated, for controlling the duration of time between the movement of said first moved element, and of both elements. 85

3. The combination with the lens of a camera; of a movable element provided with an aperture in normal register with said lens, a supplemental element provided with an aperture normally out of register therewith, means for moving said supplemental element to carry its aperture into register with said lens, means for moving both said elements to carry both apertures out of register with said lens, means for setting said elements, means for releasing the same, and means for controlling the duration of time 90 between the movement of said first moved element, and of both elements. 95

4. The combination with the lens of a camera; of a movable element provided with an aperture in normal register with said lens, a supplemental element provided with an aperture normally out of register therewith, means for moving said supplemental element to carry its aperture into register with said lens, a slide for stopping said supplemental element in such position, means for moving both elements to carry both elements out of register with said lens, means for setting said elements, means for releasing the same, and means for actuating said slide at a predetermined interval 100 of time after the movement of said supplemental element to permit the movement of both elements. 110

5. The combination with the lens of a camera; of a movable element provided 115

with an aperture in normal register with said lens, a supplemental element provided with an aperture normally out of register therewith, means for moving said supplemental element to carry its aperture into register with said lens, means for moving both said elements to carry both apertures out of register with said lens, means for setting said elements, means for releasing 10 the same, means for controlling the duration of time between the movement of said first moved element, and of both elements,

and means connected with one of said elements for preventing the actuation of said control means previous to the movement of 15 said supplemental element into lens registering position.

In testimony whereof I have signed my name to this specification in the presence of two subscribing witnesses.

WALTER CHOCIE SULLENDER.
